[57] **CLAIM**

The ornamental design for a ball-point pen, as shown and described.

DESCRIPTION

FIG. 1 is a right side elevational view of a ball-point pen showing my new design in closed position;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view of the ball-point pen in writing position, the opposite side being a mirror image thereof;

FIG. 7 is a top plan view thereof;

FIG. 8 is a bottom plan view thereof;

FIG. 9 is a front elevational view thereof;

FIG. 10 is a rear elevational view thereof.
